Primary Examiner — Cynthia R Underwood*(74) Attorney, Agent, or Firm* — Sheridan Ross P.C.(57) **CLAIM**

The ornamental design for a double loop swivel hook for a strap, as shown and described.

DESCRIPTION

FIG. 1 is a perspective view of a double loop swivel hook; FIG. 2 is a front elevation view thereof; FIG. 3 is a rear elevation view thereof; FIG. 4 is a right elevation view thereof; FIG. 5 is a left elevation view thereof; FIG. 6 is a top plan view thereof; FIG. 7 is a bottom plan view thereof; and, FIG. 8 is a perspective view of the double loop swivel hook engaged by a strap. The broken lines are included for the purpose of illustrating environment and form no part of the claimed design.
